CLAIM

The ornamental design for urine collection container, as shown and described.

DESCRIPTION

FIG. 1 is a perspective view of a urine collection container showing our new design;

FIG. 2 is a front elevational view thereof, the rear elevational view being a mirror image thereto;

FIG. 3 is a top plan view thereof,

FIG. 4 is a right side elevational view thereof;

FIG. 5 is a left side elevational view thereof;

FIG. 6 is a bottom plan view thereof; and,

FIG. 7 is a cross-sectional view thereof, taken along the line 7—7 of FIG. 3.
